[57] CLAIM

The ornamental design for a knife handle, as shown and described.

DESCRIPTION

FIG. 1 is a perspective view of a knife handle showing my new design;

FIG. 2 is a side elevation view, the opposite side view being a mirror image thereof;

FIG. 3 is a top view thereof;

FIG. 4 is a bottom view thereof;

FIG. 5 is a front end view thereof; and,

FIG. 6 is a back view thereof.

The broken line showing of a knife blade in FIGS. 1-5 is for illustrative purposes only and forms no part of the claimed design.
